Patented Dec. 17, 1957

181,742

PORTABLE ELECTRIC DRILL

Alfred W. Madl, Milwaukee, Wis., assignor to John Oster
Manufacturing Co., Milwaukee, Wis., a corporation
of Wisconsin

Application February 25, 1957, Serial No. 44,958

Term of patent 14 years

(Cl. D54—14)

Fig. 1.

Fig. 2.

Fig. 3.

Fig. 4.

Fig. 5.

Fig. 6.

Figure 1 is a perspective view of a portable electric drill embodying my new design, viewing the same from the bottom and one side thereof;

Figure 2 is a perspective view of the portable electric drill viewing the same from the rear and opposite side thereof;

Figure 3 is a perspective view of the drill directly from the top;

Figure 4 is a perspective view of the drill directly from one side;

Figure 5 is a front view of the portable electric drill; and

Figure 6 is a rear view thereof.

The dominant features of my design reside in those portions thereof shown in full lines.

I claim:

The ornamental design for a portable electric drill, as shown and described.
